UNITED STATES PATENT OFFICE.

WILLIAM SCHOLNHORN, OF NEW HAVEN, CONNECTICUT, ASSIGNOR TO
WILLIAM SCHOLNHORN & CO.

COACH-LATCH.

SPECIFICATION forming part of Letters Patent No. 314,611, dated March 31, 1885.

Application filed September 22, 1884. (No model.)

To all whom it may concern:

Be it known that I, WM. SCHOLNHORN, of New Haven, in the county of New Haven and State of Connecticut, have invented a new Improvement in Coach-Latches; and I do hereby declare the following, when taken in connection with accompanying drawings and the letters of reference marked thereon, to be a full, clear, and exact description of the same, and which said drawings constitute part of this specification, and represent, in—

Figure 1, a side view of said latch, the upper end of the lever broken off; Fig. 2, a horizontal section through the lever-pivot.

This invention relates to an improvement in that class of coach-latches which are set into a mortise in the edge of the coach-door, with a lever extending from the latch up through the window-sill in the door, and by which lever the occupant may draw the bolt from the inside of the carriage. In the best construction of these latches the bolt is simply a straight longitudinal bar extending through the face-plate of the case and supported upon the inside of the case, combined with a lever having a hook-like engagement with the bolt, a spring applied to the bolt to force it home, and which spring is relied upon to support the lever, and this spring, if the bolt is permitted to throw outward to its full extent into the keeper, will hold the lever so as to prevent its rattling, but if the bolt meet with an obstruction to prevent its entering the keeper, as by friction upon the keeper, or otherwise, then the lever is left free and produces a disagreeable rattling as the carriage runs. Again, in the usual construction, the lever is hung upon a pivot in the case, the pivot being a screw introduced through the end of the lever, tapped into the case, the lever working on the barrel or body of the screw. While such a construction serves a very good purpose as a pivot, unless the fitting of the lever upon the screw be perfect the movement of the lever frequently loosens the screw, and gives to the lever a freedom which will produce the before-mentioned disagreeable rattling.

The object of my invention is to overcome these difficulties; and the invention consists

in the construction as hereinafter described, and particularly recited in the claims.

A represents the main plate of the case; B, the face-plate; C, the bolt extending through the face-plate and supported in a bearing, D, 55 upon the under side of the case. The inner end of the bolt is turned up into hook shape, to form the arm E, against which the lever may work.

F is the lever which extends down through 60 the top of the case to near its lower edge, where it is secured upon a pivot, a. This pivot is cast or made as an integral part of the case, as seen in Fig. 2. The lower end of the lever is fitted thereon as a bearing, and so as 65 to turn freely. The end of the pivot is tapped, and into it a screw, b, is introduced, the head of which takes its bearing hard upon the pivot, but extends over slightly onto the face of the lever, so as to prevent the lever from slipping off the pivot. Under this construction 70 of the pivot the lever cannot loosen the screw, but if from any cause the screw should be loosened, the pivot remains as a firm and substantial bearing upon which the lever may 75 turn. The lever extends to the rear of the bolt, thence curved forward and downward to form an arm, d, to engage the arm E of the bolt, and so that by pulling the lever inward 80 the bolt will be drawn, as indicated in broken lines.

G is the bolt-spring. It is made from wire, one end introduced into a slot in a stud, e, formed as an integral part of the plate A. The other end of the spring extends upward to 85 engage the bolt, the tendency of the spring being to throw the bolt forward or outward.

To prevent the rattling of the lever and give it a support independent of the bolt, I apply a spring, H, upon the back of the lever. This 90 spring is made from a piece of wire, one end introduced into a slot in a stud, f, which is formed as an integral part of the case, the other bent around to take its bearing on the back of the lever, as shown. By this construction and 95 arrangement of the springs one end is firmly and immovably fixed in the case, and if perchance the springs break they are easily repaired without resort to a locksmith, as it is only necessary to remove the broken spring 100

and introduce a piece of wire bent into shape. This construction and arrangement of springs overcomes a serious difficulty heretofore experienced in this class of locks, from the fact 5 that the construction and attachment of the springs in the previous constructions are such as to require considerable mechanical skill to repair or apply them. The pivot of the lever is directly under its bearing upon the bolt, 10 the spring bears upon the lever to force it into its extreme forward position, and there hold it independent of the bolt, and so that whether or not the bolt be completely thrown, the lever will be firmly held, and the rattle of the 15 lever is impossible.

It will be understood the bolt is operated from the outside by the usual knob-like attachment working through the hub I in the usual manner, the said hub being in the usual 20 connection with the bolt, but not shown.

I claim—

1. In a coach-latch, the combination of the case, the pivot *a*, constructed as an integral part of said case and internally screw-threaded, the latch-bolt *C*, the lever *F*, hung upon said pivot and constructed to engage with the said bolt, and the headed screw *b*, introduced in the end of said pivot, the head of the screw taking a bearing upon the end of the pivot, of 25 greater diameter than the pivot, and so as to extend over the pivot onto the surface of the lever, with a spring adapted to force the said bolt outward, substantially as described.

2. In a carriage-latch, the combination of the case, the bolt *C*, extending through the face-plate, its inner end supported in a bearing, *D*, and terminating in an arm, *E*, the lever *F*, extending through the upper edge of the case downward and hung upon a pivot, *a*, below said lever, also constructed with an arm, *d*, to 35 engage the arm *E* of the bolt, the spring *H*, having one end secured in the slot of a fixed stud, *f*, formed as an integral part of the case, said spring arranged to bear upon the lever independent of the bolt, and a spring, *G*, arranged 40 to act directly upon the bolt, substantially as described.

3. In a carriage-latch, the combination of the case, the bolt *C*, arranged through the face-plate of the case, its inner end supported in a bearing, *D*, and terminating in an arm, *E*, the lever *F*, extending through the upper edge of the case downward, hung upon a pivot, *a*, formed as an integral part of the case, said lever constructed with an arm, *d*, to engage 50 the arm *E* of the bolt, the spring *G*, made from wire, one end arranged in a slot in a stud, *e*, made as an integral part of the case, the other engaged with the bolt, and a spring, *H*, arranged to bear upon the lever independent of 55 the bolt, substantially as described.
